DESIGN FOR A BANNER BAR PIN

Robert T. Dieges, Yonkers, N. Y.

Application July 29, 1936, Serial No. 64,113

Term of patent 3½ years

To all whom it may concern:

Be it known that I, Robert T. Dieges, a citizen of the United States, residing at Yonkers, in the county of Westchester and State of New York, have invented a new, original, and ornamental Design for a Banner Bar-Pin, of which the following is a specification, reference being had to the accompanying drawing, forming part thereof.

Fig. 1 is a view in elevation and Fig. 2 a side elevation of a banner bar-pin showing my new design.

I claim:

The ornamental design for a banner bar-pin, as shown.

ROBERT T. DIEGES.
